UNITED STATES PATENT OFFICE

CARL D. BROWN, OF HOPEDALE, MASSACHUSETTS, ASSIGNOR TO DRAPER CORPORATION,
OF HOPEDALE, MASSACHUSETTS, A CORPORATION OF MAINE

WARPER

Application filed December 21, 1928. Serial No. 327,547.

This invention relates to a warper for winding warp yarns drawn from a suitable supply such as a creel onto a warp beam of that type in which the warp beam rests against a driving drum and is rotated by the frictional engagement of the drum with the warp mass as the warps are wound on the beam. In this type of machine, the warp beam moves away from the driving drum as the warps 10 are wound on the beam due to the increasing diameter of the warp mass.

The object of this invention is to provide a construction in this type of warper which will enable the warper to be run at the high 15 speeds now demanded by the trade. When a warper of this type is run at high speed, the warp beam frequently jumps and vibrates, injuring the yarn more or less and preventing the yarn mass being wound under even tension and with the desired degree of homogeneity.

It is the object of the present invention further to provide friction-controlled means acting to prevent such jumping or vibration 25 of the warp beam in which the amount of friction shall be gradually reduced as the total weight of the beam increases due to the increase in the weight of the yarn mass as the winding operation proceeds.

It is the further object of the invention to provide such a construction in which the friction-controlled means acts upon any movement of the beam toward the driving drum to present a greater resistance at the end of 35 such movement than at the beginning to a continued or further movement of the beam away from the driving drum so that jumping or vibration of the beam is reduced to the minimum.

It is the further object of the invention to provide for the adjustment of the friction-controlled means to accord with the conditions prevailing in a particular warper and also to provide means for enabling the beam 45 to be doffed and a fresh beam put in place without disturbing the adjustments.

The object of the invention is further to provide a simple, efficient and durable form of construction operating upon the friction 50 control principle for enabling this type of

warper to be run at high speed without deleterious jumping or vibration of the beam.

These and other objects and features of the invention will appear more fully from the accompanying description and drawings and will be particularly pointed out in the claims. 55

Since the invention is concerned solely with the control of the warp beam during the winding operation, the preventing of the jumping or vibration of the warp beam and the provisions for doffing the warp beam, and as the other features and mechanisms of the warper may be of any suitable construction and form, and as the general principle and operation of a warper are well-known and familiar to those skilled in the art, it is only necessary here to illustrate and describe those portions of a warper directly concerned with one preferred form of embodiment of the present invention. 60 65 70

In the drawings:

Fig. 1 is a side elevation of a warper with a simple and preferred form of the invention embodied therein and with elements of the warper not concerned with the present invention omitted. 75

Fig. 2 is a view on a larger scale of the friction device shown in Fig. 1, partially in vertical cross section and looking at the side thereof opposite to that shown in Fig. 1. 80

Fig. 3 is a view in transverse cross section taken on the line 3—3 of Fig. 2.

Fig. 4 is a detail view showing a clamp connection at one end of the friction band.

The warper comprises end frames such as 1 standing on the floor 2. A shaft 3 mounted in suitable bearings in the end frames supports the usual driving drum 4 and is driven at high speed in any suitable manner from a suitable source of power. The warp beam may be of any suitable type comprising the usual cylindrical barrel, the heads 5 and gudgeons 8. The barrel of the beam rests against the driving drum 4 and the warps 6 extend as usual from a creel or other supply through usual adjunctive devices, through the comb 9 over the roll 10 and are secured at their ends in any suitable manner to the barrel of the warp beam. Consequently as the driving drum 4 is rotated, the frictional engagement 85 90 95 100

of the drum with the beam barrel or the warp mass thereon rotates the beam, winding the warp yarns thereon. The yarn mass 11 on the warp beam therefore gradually increases in diameter until the beam is filled. Consequently also the total weight of the beam and yarn mass likewise gradually increases.

Any suitable means may be employed for supporting the warp beam gudgeons so as to enable the warp beam to rest against the driving drum and to move away from the driving drum as the yarn is wound on the beam by the frictional engagement of the drum therewith. Such means, as well as the frictional controlling devices with which this invention is particularly concerned, are desirably the same at both sides of the warper so that it is sufficient to illustrate the construction at one side. The means for supporting the warp beam gudgeons is shown as of an ordinary type. At each side of the warper a supporting arm 12 is pivotally mounted on the stud 13 carried by a link 14 pivoted to the crank 15. By turning the shaft 16, through interposed and familiar mechanism not necessary here further to describe, the crank arm 15 is turned about its axis 17 to lower and raise the arms 12 for doffing and replacing the beam. Each warp beam gudgeon 8 is supported in a bearing sleeve 18 seated in a bearing seat 19 formed on the supporting arm and a bearing cap 20 pivoted at 21 serves to hold the bearing sleeve in place. Thus it will be seen that as the warp yarns are wound on the beam, the diameter of the warp mass increases and the supporting arms swing forward and upward as the beam moves away from the driving drum.

In this invention a frictional resistance is presented to control this movement of the warp beam and this frictional resistance decreases as the mass of yarn increases on the warp beam. It is desirable that there shall be no great variation throughout the winding operation in the pressure between the driving drum and the warp beam. Otherwise the compactness of the warp mass will vary. But as the total weight of the warp beam and yarn mass gradually increases from the beginning to the end of the winding operation, if this were the only factor acting to cause pressure between the friction drum and the warp beam, this pressure would gradually increase. But with a friction-controlled device applied in addition to the warp beam, it is possible to control the total effective pressure between the driving drum and the warp beam as required and preferably so as to maintain it substantially uniform throughout the winding operation. Consequently in this invention the amount of friction acting to prevent movement of the warp beam away from the driving drum is gradually reduced from the beginning to the end of the winding

operation so as to offset the increase in the weight of the warp beam and yarn mass.

A preferred form of construction embodying the invention is shown in Fig. 1 and more in detail in Figs. 2 and 3 and, as noted, is the same at both sides of the warper. A bracket 22 is bolted at 23 to the side frame 1 and extends upwardly therefrom beneath the supporting arm 12. This bracket is formed to present an extended bearing hub 24 and in this hub is rigidly mounted a stud 25 extending parallel with the axes of the driving drum and warp beam. A friction drum 26 having the annular flange 27 and a base 28 is secured to the bracket 22 and is rotarily adjustable about the hub 24 by means of bolts 29 passing through suitable spaced holes 30 in the base and through the bracket 22. An anchor arm 31 is provided with a hub 32 journaled on the stud 25. This arm extends to the outside of the friction drum and at its outer end is provided with an anchor stud 33 having a threaded shank 34 passing through the end of the arm and held in place by a nut 35. This anchor stud extends transversely across and adjacent the flange 27 of the friction drum. A helical spring 36 surrounds the hub 32 of the arm and has one end 37 connected to the hub and the other end 38 connected to a collar 39 mounted and rotarily adjustable on the end of the stud 25 by means of a removable pin 40 extending through aligned holes in the collar and stud.

A friction band is connected at one end to the stud 33 on the arm 31 and extends therefrom encircling the friction drum and at its other end is connected to the supporting arm 12. This friction band may be of any suitable material for the purpose. As illustrated, it comprises a heavy fabric strap 41, an intermediate steel strip 42 and a cork facing 43. At the anchor end the steel strip 42 is bent into a loop around the stud 33, back upon the main body of the friction band and all the layers are there secured together by rivets 44. At some distance from this end a suitable clamping member 45 holds the component parts of the friction band together, but from there on the strap 41 is free to separate from the other members of the band which are secured together at their opposite ends by a rivet 46. The other end of the strap 41 passes through the looped end 47 of a rod 48 and is bent back upon the body of the strap and clamped thereto between two plates 49 which are drawn together by bolts 50 passed through the plates adjacent the edges of the strap. The rod 48 extends through bifurcated lugs 51 projecting from the bearing seat and bearing cap of the supporting arm and has pivoted to it at its upper end 52 a cam lever 53.

Stops for limiting the rotary movement of the arm 31 in either direction are provided

and are shown as lugs 54 and 55 formed integral with and projecting from the base 28 of the friction drum.

The anchor stud 33 for the end of the friction band moves circumferentially of the fixedly mounted friction drum and the spring 36 acts yieldingly to move this anchor for the friction band in a direction opposite to the pull exerted by the warp beam through the friction band as the winding operation proceeds and the warp beam moves away from the driving drum. This spring 36 may be adjusted by rotarily adjusting the collar 39 so as to vary the tension exerted thereby on the friction band but when once adjusted the amount of resistance to the movement of the warp beam or supporting arm away from the driving drum will be substantially dependent upon the length of the arc of the friction drum engaged by the friction band. When the beam is empty and the winding operation is about to begin, the length of this arc may be adjusted by adjusting the rotary position of the friction drum by means of the bolts 25 and by making the length of the friction band such as when connected to the supporting arm to stand taut. Then as the winding operation proceeds and the supporting arm moves away from the driving drum, the friction band steadily slips around the friction drum, drawing the anchor with it and consequently gradually diminishing the arc of its engagement with the friction drum. Consequently it will be seen that as the total weight of the beam and yarn mass increases, the frictional resistance opposed by this invention to the movement of the beam away from the driving drum decreases and the relation between the rate of increase and the rate of decrease may be fixed as desired by proportioning the parts and by making the adjustments provided. Thus a very accurate control of the pressure between the driving drum and the warp beam may be had under any set of conditions.

Any movement of the beam toward the driving drum immediately relieves the strain or pull on the friction band thus substantially diminishing the friction between the friction drum and the friction band and consequently permitting the spring 36 to act to move the anchor in the direction opposite to the direction of pull on the friction band and consequently increase the length of the arc of the friction drum encircled by the friction band. It will be seen, therefore, that the device acts to neutralize or prevent jumping or vibration on the warp beam. Any such movement of the warp beam necessarily involves both a movement away from and a movement toward the driving drum. The former meets the powerful resistance of the friction device while the latter, because of the principle just set forth, results in a greater resistance being presented to any continued

or further movement of the beam away from the driving drum.

The invention thus presents a friction-controlled means resisting with a gradually reducing amount of friction the movement of the beam away from the driving drum and further acting to neutralize or prevent jumping or vibration of the beam as when running at high speed.

When the beam has been wound full of yarn and it is desired to doff the beam, the friction device will be exerting the minimum amount of friction. By seizing the free end of the lever 53 and rocking its cam end about the projecting end of the upper lug 51, the bar 48 is readily pried out free from both lugs 51, thus freeing the beam supports from the friction device. When a fresh beam is placed in position, the reverse operation is performed and the lever 53 in this case acts to stretch the friction band firmly into initial position.

Having thus described the invention, what is claimed as new, and desired to be secured by Letters Patent, is:

1. A warper comprising a driving drum, a warp beam supported to rest against the drum and to move away from the drum as the yarn is wound on the beam by the frictional engagement of the drum therewith, a fixedly mounted friction drum, an anchor movable circumferentially of the friction drum, a friction band connected at one end to the beam, encircling the friction drum and connected at the other end to the anchor, and means for yieldingly moving the anchor in a direction opposite to the pull exerted by the beam on the friction band.

2. A warper comprising a driving drum, a warp beam supported to rest against the drum and to move away from the drum as the yarn is wound on the beam by the frictional engagement of the drum therewith, a fixedly mounted friction drum, an anchor movable circumferentially of the friction drum, a friction band connected at one end to the beam, engaging an extended arc of the friction drum and connected at the other end to the anchor, and means for yieldingly resisting the movement of the anchor due to the pull of the friction band by the warp beam, the said movement of the anchor due to said pull acting gradually to diminish the length of the arc of the friction drum engaged by the friction band and thereby the resistance to the movement of the beam away from the driving drum and the said yielding means acting to move the anchor in the opposite direction upon any movement of the beam toward the friction drum thus to neutralize vibration of the beam.

3. A warper comprising a driving drum, a warp beam supported to rest against the drum and to move away from the drum as the yarn is wound on the beam by the frictional engagement of the drum therewith, a

fixedly mounted friction drum, an anchor movable circumferentially of the friction drum, a friction band connected at one end to the beam, encircling the friction drum and connected at the other end to the anchor, means for yieldingly moving the anchor in a direction opposite to the pull exerted by the beam on the friction band, and means for adjustably limiting the movement of the anchor in said direction.

4. A warper comprising a driving drum, a warp beam supported to rest against the drum and to move away from the drum as the yarn is wound on the beam by the frictional engagement of the drum therewith, a fixedly mounted friction drum, an anchor movable circumferentially of the friction drum, a friction band connected at one end to the beam, encircling the friction drum and connected at the other end to the anchor, means for yieldingly moving the anchor in a direction opposite to the pull exerted by the beam on the friction band, a stop lug on the drum for limiting the movement of the anchor in the said direction, and means for rotarily adjusting the position of the friction drum thus to adjust the position of said stop lug.

5. A warper comprising a driving drum, a warp beam supported to rest against the drum and to move away from the drum as the yarn is wound on the beam by the frictional engagement of the drum therewith, a fixedly mounted friction drum, an anchor movable circumferentially of the friction drum, a friction band connected at one end to the beam, encircling the friction drum and connected at the other end to the anchor, a spring acting to move the anchor in a direction opposite to the pull exerted by the beam on the friction band and means for adjusting the tension of said spring.

6. A warper comprising a driving drum, a warp beam supported to rest against the drum and to move away from the drum as the yarn is wound on the beam by the frictional engagement of the drum therewith, a fixedly mounted friction drum, a stud extending axially of the friction drum, an arm journaled on the stud and having its ends extending across the periphery of the friction drum to form an anchor, a helical spring on the stud secured at one end to the arm and at the other end to the stud and a friction band connected at one end to the beam, encircling the friction drum and connected at the other end to the anchor.

7. A warper comprising the construction defined in claim 6, in which a collar is provided rotarily adjustably mounted on the stud and in which the helical spring is secured to the collar and thus to the stud, thus enabling the tension of the spring to be adjusted.

8. A warper comprising a driving drum,

a warp beam, a support for the warp beam acting to hold the warp beam resting against the drum and to move with the warp beam away from the drum as the yarn is wound on the beam by the frictional engagement of the drum therewith, a cam device detachably mounted on the said support, a fixedly mounted friction drum, an anchor movable circumferentially of the friction drum, a friction band connected at one end to the cam device, encircling the friction drum and connected at the other end to the anchor, and means for yieldingly moving the anchor in a direction opposite to the pull exerted on the friction band, the cam device when in working position acting to hold the friction band taut and when moved to detaching position acting to relieve the strain on the friction band.

9. A warper comprising a driving drum, a warp beam having gudgeons, a support for the warp beam acting to hold the warp beam resting against the drum and to move with the warp beam away from the drum as the yarn is wound on the beam by the frictional engagement of the drum therewith, the said support having a bearing seat and a bearing cap for the warp beam gudgeon, a cam lever carried by the support, a fixedly mounted friction drum, an anchor movable circumferentially of the friction drum, a friction band connected at one end to the cam lever, encircling the friction drum and connected at the other end to the anchor, and means for yieldingly moving the anchor in a direction opposite to the pull exerted on the friction band, the cam lever acting when in working position to lock the bearing cap in position and to hold the friction band taut and acting when swung to doffing position to release the bearing cap and also to release the strain on the friction band.

In testimony whereof, I have signed my name to this specification.
